PERFLUORO-SUBSTITUTED ALIPHATIC ACIDS
AND DERIVATIVES THEREOF

George V. D. Tiers, St. Paul, Minn., assignor to Minnesota Mining and Manufacturing Company, St. Paul, Minn., a corporation of Delaware

No Drawing. Filed June 26, 1957, Ser. No. 668,027

23 Claims. (Cl. 260—23)

This invention relates to terminally perfluoroalkylated aliphatic carboxylic acids and to derivatives thereof.

Perfluoroaliphatic carboxylic acids and acids of similar type in which there is interposition of a methylene group between the carboxyl and perfluoroalkyl groups are known. The latter may conveniently be designated as 2,2-dihydroperfluoroalkyl carboxylic acids. These known compounds are strong acids containing over 50% combined fluorine in which the strength of the ordinary carboxyl group is enhanced by the proximity of the highly fluorinated alkyl groups. Fluorinated acids and derivatives thereof have desirable oleophobic and hydrophobic properties; but the strongly acid nature of the known compounds introduces certain disadvantages. For example, the perfluoro carboxylic acids approach the acidity of mineral acids and are highly corrosive and dangerous to handle. Their derivatives are relatively easily hydrolyzed and the metallic salt complexes of these strong acids tend to be labile. The 2,2-dihydroperfluoro-carboxylic acids are unstable in alkaline media.

It is an object of this invention to provide stable acids and derivatives thereof possessing the desirable oleophobic and hydrophobic properties of perfluoroalkyl groups, but in which the ordinarily strong acidity of such perfluorinated carboxylic acids has been moderated. It is a further object of the invention to provide polymerizable derivatives of such acids. Still further objects of the invention will be apparent from the following disclosure.

In accordance with the above and other objects of the invention, it has been found that acids represented by the general formula:

wherein R_f is a monovalent, functionally unsubstituted perfluorinated group having from 4 to 12 carbon atoms and includes perfluorinated alkyl and cycloalkyl radicals, and R is a straightchain alkylene group having from 1 to 12 carbon atoms, have low acid strength while unexpectedly retaining the desirable oleophobic properties of the perfluorinated group.

As illustrative examples of acids coming within the scope of the present invention there may be mentioned: 5-perfluorobutylpentanoic acid, 7-perfluoroamylheptanoic acid, 6-perfluorododecylhexanoic acid, omega-perfluorobutyl-myristic acid, 9-perfluoroctyl-nonanoic acid, 5-perfluoroctylpentanoic acid, 11-perfluoroctyl-hendecanoic acid, 12-perfluoroctyl-dodecanoic acid, and 8-perfluorocyclohexyl octanoic acid.

The presence of the chain of 3 or more carbon atoms between the R_f group, as defined above, and the carboxyl group, renders these acids less strongly acid than the perfluorinated acids lacking this alkylene chain by as much as 1000 fold or more. For certain purposes this markedly lowered acidity is highly desirable. It results in greatly increased resistance of the esters of the acids of the invention to hydrolysis in neutral and basic media. It promotes increased stability of the metallic salt-complexes, such as for example the chromium complex, and it greatly reduces the corrosiveness of the free acids and of the amine or ammonium salts toward electropositive

2

metals and toward skin tissues. Surprisingly, at the same time the acids of the invention and their derivatives retain the desirable oleophobic properties conferred by the R_f group and, when the alkylene group R is in the range of 1 to 12 carbon atoms, the soluble salts of these acids have a balance of fluorophilic, oleophobic and hydrophilic properties possessing particular value as emulsifying agents for use in the polymerization of monomers of the fluorocarbon type. The term "fluophilic" is here coined to describe the novel property of affinity for fluorocarbon-type materials, and includes both solubility and wettability phenomena involving such materials. For example, the vinyl and allyl esters of the chlorinated precursor intermediates of the acids of the present invention, of the type $R_f-CH_2-CHCl-(CH_2)_nCH_2CO_2H$ wherein n is 0 to 11, as well as the vinyl and allyl esters of the acids of the invention themselves, can be emulsion-polymerized in the presence of salts of these latter acids as emulsifying agents.

Included within the scope of the invention are the simple derivatives of the described perfluoroalkylated aliphatic acids. It is convenient to designate these derivatives of the acids of the invention by the term carboxyl-linked derivatives. This term as used herein signifies derivatives formed both by replacement of the hydrogen ion of the carboxyl group by another cation, as in the salts and complexes, and derivatives formed by formal dehydration reactions as for example acyl halides, anhydrides, amides, amidines, nitriles, hydrazides, peroxides, esters, orthoesters and the like.

Broadly speaking, the acids of the invention can be produced by successively dehydrohalogenating penultimately chlorinated acids formed, for example, by desulfonylative addition of a perfluorinated sulfonyl chloride to a terminally unsaturated aliphatic carboxylic acid and reducing the resultant fluorinated unsaturated acids, for example, by hydrogenation. Intermediate terminally unsaturated acids having the desired carbon chain lengths for preparation of the compounds of the invention can be prepared by hydrolysis of the alkenylmalonic esters produced by the repeated use of the malonic ester synthesis, described in the textbook of R. B. Wagner and H. D. Zook, entitled *Synthetic Organic Chemistry*, pages 427-428, John Wiley and Sons, Inc., New York, 1953.

The following series of equations, in which R_f has the same significance as hereinabove, illustrates the preparation of an ω -perfluoroalkyl hendecanoic acid.

Alternatively, the compounds of the invention are conveniently and directly prepared by catalytic protodechlorination (reductive dehydrohalogenation) of the halogenated acids produced as set forth above.

Still another method by which the acids of this invention can be produced is by addition of a perfluoroalkyl iodide to an unsaturated aliphatic acid, followed by catalytic protodeiodination, as illustrated by the equation:

wherein R_f again has the significance described hereinabove. By the catalytic protodehalogenation processes the reduced acids are formed without the necessity for intermediate isolation of unsaturated acids. While it is possible that the reactions described proceed step-wise so that fluorocarbon-substituted unsaturated acids are first formed in the reaction mixture and then are reduced, whereby unsaturated impurities might remain in the product acids if hydrogenation conditions were not vigorous enough, such impurities are readily completely reduced, when necessary, by continued or repeated hydrogenation. Their formation is precluded when the hydrogenation step is carried out under sufficiently vigorous conditions. However, if desired, isolation of the corresponding perfluorinated unsaturated acids can be accomplished readily by treatment of the halogenated acids by excess alkali in hot water or alcohol. Since these unsaturated acids are ordinarily oily mixtures of the cis and trans stereoisomeric modifications, which are not readily characterized or separated, they may be less desirable from the standpoint of handling in large-scale manufacturing processes.

The perfluorinated acids of the invention are seen to possess in part the characteristics of organic carboxylic acids and in part those of perfluorinated acids. They are, generally speaking, low-melting somewhat waxy white or slightly colored solids which are substantially insoluble in water and hydrocarbon solvents, and are soluble in fluorocarbon solvents. They further possess the common characteristics of both groups of acids, namely, that of forming salts with cations of metals such as sodium, potassium, calcium, aluminum, zinc, copper, iron, manganese, zirconium and the like and ammonium ion and alkyl-substituted ammonium ions such as ethylammonium, piperidinium, dimethylammonium, trimethylammonium and tetramethylammonium ions. Depending upon the particular cation these salts are readily soluble in water as, for example, the sodium, potassium and ammonium salts; or insoluble, as for example, the basic aluminum salt. The basic aluminum salt is oleophobic and hydrophobic, but is unexpectedly found to be highly fluorophilic, being soluble in fluorocarbon solvents.

The acids of the invention can be converted to the corresponding acyl halides, for example to the acyl chloride, by treatment with conventional halogenating agents, such as phosphorus pentachloride and thionyl chloride; and to the acyl fluoride, by treatment of the acyl chloride with hydrogen fluoride; and the like. Similarly, by replacement of the chlorine with bromine or iodine, as by reacting with calcium bromide or calcium iodide, respectively, the acyl chlorides can be converted to the corresponding acyl bromides or acyl iodides. The acids themselves, or especially their anhydrides or their acyl halides, can be reacted with alcohols to produce esters, with ammonia and primary or secondary amines to produce amides and substituted amides respectively. Dehydration of the amides yields the corresponding nitriles. Treating the acids of the invention and especially derivatives thereof with hydrazine produces hydrazides, by the methods commonly employed for the purpose. Thus it is seen that the carboxyl group of the acids of the invention is capable of undergoing all of the ordinary reactions of the aliphatic carboxyl group. The esters can also be produced by transesterification of the acids with suitable esters such as vinyl acetate, this method being particularly useful for preparation of esters for which the free alcohol is not stable; or by catalytic esterification, particularly under conditions such that water is eliminated from the reaction mixture. Other conventional reactions of carboxylic acids are also exhibited by the acids of the present invention.

The acids of the invention have utility for the formation of complex derivatives of value in treatment of leather. Derivatives of this type, the method for their preparation and their use for this purpose are disclosed

in the copending application of Olson et al., Serial No. 640,569, filed February 18, 1957.

The vinyl and allyl esters of the acids of the invention can be homopolymerized and copolymerized inter se as well as with other monomers and low polymers to form polymeric materials comprising recurring units having the formula

10

15

wherein R and R_f have the significance set forth hereinabove and n is 0 or 1. These homopolymers and copolymers are suitable for rendering paper and textiles oil-resistant and water repellent.

20

The following illustrative examples will more specifically describe the compounds of the invention and the processes for their preparation.

Example I

A mixture of 26.8 g. (0.052 mole) of perfluorooctanesulfonyl chloride and 5.0 g. (0.050 mole) of 4-pentenoic acid (allyl-acetic acid) is refluxed for four hours at about 120-145° C. in the presence of a catalytic amount (1.0 g.) of di-tertiary butyl peroxide. The reaction mixture is fractionally distilled under reduced pressure and the fraction boiling at about 100° C. at 0.01 mm. is collected. After recrystallization from a mixture of chloroform and carbon bisulfide, the 4-chloro-5-(perfluorooctyl)-pentanoic acid thus prepared melts at about 89-90° C. *Analysis*.—Found, 28.3% C, 57.7% F, 6.47% Cl (not significantly changed by recrystallization); calculated, 28.1% C, 58.2% F, 6.39% Cl.

The 4-chloro-5-(perfluorooctyl)-pentanoic acid thus prepared is hydrogenated by shaking a solution of 8.00 g. (0.0145 mole) of the acid and 2.5 g. (0.062 mole) of sodium hydroxide in a mixture of 30 ml. of water and 30 ml. ethanol for 3 hours at 140° C. in a rocking high-pressure hydrogenation apparatus, in the presence of 4 g. of Raney nickel catalyst and with hydrogen supplied at 2500 p.s.i. pressure. After removal of the catalyst and evaporation to dryness, an amorphous residue is obtained comprising sodium 5-(perfluorooctyl)-pentanoate. By dissolving this residue in water followed by acidification of the resulting solution, the saturated perfluoroalkyl aliphatic acid formed by hydrogenation is recovered as a waxy white solid, which can be distilled at 100° C. at 0.02 mm. pressure. After recrystallization from carbon bisulfide, the 5-(perfluorooctyl)-pentanoic acid thus prepared melts at about 86.5-87.3° C. *Analysis*.—Found, 30.0% C, 61.9% F; calculated, 30.0% C, 62.1% F.

By repeating the foregoing procedure, employing perfluoro-n-pentanesulfonyl chloride and perfluorododecane-sulfonyl chloride (prepared by the process of Brice et al. as disclosed in U.S. Patent No. 2,732,398) instead of perfluorooctanesulfonyl chloride, there are obtained, respectively, 5-(perfluoropentyl)-pentanoic acid and 5-(perfluorododecyl)-pentanoic acid.

Likewise, when 3-butenoic acid, 6-heptenoic acid and 13-tridecanoic acid are employed instead of 5-pentenoic acid in carrying out the procedure of this example, there are obtained, respectively, the corresponding 4-(perfluorooctyl)-butyric acid, 7-(perfluorooctyl)-heptanoic acid and 13-(perfluorooctyl)-tridecanoic acid.

Example II

An electrically heated rocking autoclave of 187 ml. capacity is charged with 37.5 grams of purified 11-perfluorooctyl-10-chlorohendecanoic acid (prepared by reaction of perfluorooctanesulfonyl chloride and 10-hendecenoic acid by the method described in the preceding example), 8.4 grams of potassium hydroxide, 10 ml.

of water, 60 ml. of absolute ethanol, and 6.0 grams of Raney nickel catalyst. Hydrogen is introduced at 3000 p.s.i. pressure and the autoclave is rocked for four hours while heating at 150° C. At the end of four hours the autoclave is cooled to about 50° C., flushed with nitrogen and opened. The contents are removed and cautiously filtered hot (avoiding spontaneous ignition of the catalyst), and the catalyst is washed with several 50 ml. portions of hot ethanol. The combined filtrate and washings are evaporated to dryness, dissolved in water and acidified with dilute hydrochloric acid, whereupon a waxy precipitate forms and is collected and dried. After distillation at reduced pressure, the 11-(perfluoroctyl)-hendecanoic acid formed in the reaction melts at about 83.5° to 84.5° C. *Analysis.*—Found, 37.9% C, 53.3% F; calculated, 37.8% C, 53.5% F.

A mixture of 6 g. (0.01 mole) of 11-perfluoroctyl-hendecanoic acid and 100 ml. of 0.1 M alcoholic sodium hydroxide is refluxed until substantially all of the acid has dissolved. The reaction mixture is then evaporated to dryness on the steam bath or in vacuo. The soapy white residue is the sodium salt of 11-(perfluoroctyl)-hendecanoic acid.

In the same way, but by use of an equimolar amount of potassium hydroxide, there is prepared the potassium salt of 11-(perfluoroctyl)-hendecanoic acid.

Likewise, by admixture of an aqueous solution of aluminum chloride and an alcoholic solution containing a slight stoichiometric excess of the acid, a precipitate of the aluminum salt of 11-(perfluoroctyl)-hendecanoic acid is formed. The somewhat sticky, amorphous precipitate is washed with water and dried. It is soluble in xylene hexafluoride.

Example III

A mixture of 54 g. (0.0895 mole) of 11-(perfluoroctyl)-hendecanoic acid and 35 g. (0.28 mole) of thionyl chloride is warmed under reflux on a steam bath for about 1 hour, allowed to stand overnight at room temperature, and then heated to the point of vigorous refluxing for 2 hours. The resulting reaction mixture is transferred to a distilling flask and excess thionyl chloride is removed by distillation. Traces of thionyl chloride still remaining are removed by heating under reduced pressure and the residual 11-(perfluoroctyl)-hendecanoyl chloride is fractionally distilled under reduced pressure, the fraction boiling from 110 to 125° C. at 0.015 mm. of mercury pressure being collected. After redistillation, the 11-(perfluoroctyl)-hendecanoyl chloride thus prepared boils at 125° at 0.015 mm. pressure. *Analysis.*—Found, 37.3% C, 5.7% Cl; calculated, 36.7% C, 5.7% Cl.

Example IV

A small amount of 11-(perfluoroctyl)-hendecanoyl chloride prepared by the procedure of Example III is added to a stoichiometric excess of 28% ammonium hydroxide. After standing for a few minutes at room temperature a precipitate of insoluble 11-perfluoroctyl-hendecanamide forms and is collected and dried. Recrystallization from xylene hexafluoride yields white, crystalline, 11-(perfluoroctyl)-hendecanoic amide melting at about 103-115° C.

Example V

Omega-perfluoroctylhendecanoic acid is converted to a chromium complex by the method described in U.S. Patent 2,662,835 for fully fluorinated acids. The resulting green solid complex material cannot be structurally characterized by analysis. It is applied to chrome-tanned, split and shaved cowhide sides previously lightly retanned with vegetable extract in a wet handling drum and conventionally dyed. The chromium complex is applied as follows: The leather handling drum is drained, and fresh float water is introduced at 100° F. in amount approximately equal to the weight of the wet leather, the

pH being adjusted to about pH 3.5-4.0 using formic acid. A 30% alcoholic chromium complex solution having a chromium:acid mole ratio of 3:1 is added in amount sufficient to provide chromium complex equal to 3% of the dry weight of the leather. The leather is then drummed until the green color of the solution disappears. The treated leather is rinsed for 2 minutes and set out and dried; and finished in the usual manner. Leather thus prepared has high flexibility and is markedly water and oil-repellent, with good tensile strength.

Example VI

Another route for the preparation of the acids of the present invention is exemplified by the following procedure:

A solution of 5.0 grams (.00765 mole) of omega-perfluoroctyl-hendecyl bromide (prepared by the reduction of omega-perfluoroctyl-hendecanoic acid with lithium aluminum hydride to the corresponding alcohol followed by treatment with hydrogen bromide) in about 70 ml. of absolute ethanol is mixed with 2 ml. of an aqueous sodium cyanide solution containing 0.008 mole sodium cyanide and refluxed for 72 hours. The nitrile of omega-perfluoroctyl-dodecanoic acid is thus formed. If desired, the omega-perfluorododecanonitrile can be isolated, as by removal of the solvent by evaporation followed by water-washing to dissolve the soluble constituents of the reaction mixture and drying of the water-insoluble residue, followed by recrystallization from cold ether, chloroform or alcohol. However, without isolation from the reaction mixture the omega-perfluoroctyl dodecanonitrile can be hydrolyzed to form the corresponding ω -perfluoroctyl dodecanoic acid by addition to the alcoholic reaction mixture of 2.24 grams (0.04 mole) of potassium hydroxide dissolved in about 4 ml. of water and refluxing for 24 hours. Saponification is not complete under these conditions, and both the amide and the acid can be isolated from the reaction mixture. The alkaline alcoholic reaction mixture is diluted with water and boiled to expel a portion of the alcohol, acidified by addition of concentrated hydrochloric acid and chilled thoroughly. The precipitate which forms is collected, washed with water and dried. Extraction with absolute ether furnishes a soluble fraction and an insoluble fraction. Recrystallization of the ether-soluble fraction from hexane yields 12-perfluoroctyl dodecanoic acid melting at about 80°-82° C. *Analysis.*—Found, 38.9% C, 52.2% F; calculated, 38.8% C, 52.2% F. Recrystallization of the ether-insoluble fraction from xylene hexafluoride furnishes 12-perfluoroctyl dodecanoic amide melting at about 115° to 118° C. *Analysis.*—Found 39.3% C, 2.2% N; calculated, 40.0% C, 2.3% N. The amide is converted to potassium 12-perfluoroctyl dodecanoate by prolonged refluxing with aqueous alcoholic potassium hydroxide.

Example VII

To a mixture of 65 grams (0.75 mole) of vinyl acetate, 75 grams (0.125 mole) of 11-perfluoroctyl-10-hendecenoic acid (prepared by refluxing omega-perfluoroctyl-10-chlorohendecanoic acid for 2 hours with excess alcoholic potassium hydroxide and isolating and distilling the resultant acid) and 1.5 grams of mercuric acetate is continuously added 0.36 gram of concentrated sulfuric acid. The reaction mixture is allowed to stand at room temperature for about thirteen days to effect ester interchange. One gram of sodium acetate is added, the excess vinyl acetate is removed by evaporation under reduced pressure, and the residue is transferred to a distillation flask and fractionally distilled rapidly under reduced pressure. The fraction boiling at 50° to 140° C. at the pressure of 0.4 mm. of mercury is collected and redistilled through a Vigreux column to give vinyl 11-perfluoroctyl-10-hendecenoate, a colorless liquid boiling at 122-124° at about 0.015 mm. of mercury pressure, and possessing $n_D^{25}=1.3768$. *Analysis.*—Found, 40.3% C, 51.5% F; calculated, 40.3% C, 51.6% F.

Example VIII

By employing substantially the same procedure as that set forth in Example VII, the vinyl ester of 11-(perfluoroctyl)-hendecanoic acid is prepared. In this case, because of the lower solubility of the saturated acid, it is necessary to heat the mixture of 9 grams of acid, 7.75 grams of vinyl acetate and 0.18 gram of mercuric acetate to 40° C. until the acid does not precipitate from the mixture on cooling to room temperature. The mixture is then allowed to stand at room temperature for five days and worked up. The fraction boiling at about 125 to 132° C. at 0.35 mm. of mercury pressure is collected. The vinyl ester of 11-perfluoroctyl-hendecanoic acid thus prepared is a soft solid which melts at about 38° C. *Analysis.*—Found, 40.4% C, 51.2% F; calculated, 40.1% C, 51.3% F. The amount of mercuric acetate employed in the procedure can be varied slightly with substantially the same results.

Example IX

Vinyl 11-perfluoroctyl-10-chloro-hendecanoate, prepared by esterification of 11-perfluoroctyl-10-chloro-hendecanoic acid with vinyl acetate under conditions of ester interchange as hereinbefore disclosed, can be polymerized either in bulk or in emulsion form. A mixture of 1.0 gram of vinyl 11-perfluoroctyl-10-chloro-hendecanoate and 0.01 g. of 25% solution of acetyl peroxide in dimethyl phthalate is heated under vacuum in a sealed ampoule at 50° C. for 42 hours. A rather hard, opaque, waxy polymer is formed which is insoluble in acetone. It is dissolved in xylene hexafluoride and precipitated with methanol, collected and dried in vacuum at 50° C.

Emulsion polymerization of vinyl 11-perfluoroctyl-10-chloro-hendecanoate is effected using 1.0 g. monomer, 1.8 g. water, 0.05 g. of the potassium salt of 11-(perfluoroctyl)-10-hendecanoic acid and 0.0030 g. potassium persulfate in an ampoule which is frozen, evacuated and thawed for two cycles before heating at 50° C. for 42 hours. The resulting latex contains 10% polymer solids, with inherent viscosity in 2:1 methyl perfluorobutyrate-acetone of about 0.32.

Example X

Vinyl 11-perfluoroctyl-hendecanoate is emulsion homopolymerized by heating a mixture of 0.25 gram of the monomer, 0.46 g. of 2.8% aqueous dodecylamine hydrochloride solution and 0.0013 g. potassium persulfate. The resulting latex contains 14.8% solids, indicating 38% conversion. The intrinsic viscosity in 2:1 methyl perfluorobutyrate-acetone is 0.32.

Better conversion is obtained when highly fluorinated emulsifying agents are used in place of the dodecylamine hydrochloride and when a portion of the water is replaced by a solvent such as trifluoroethanol or acetone. When the procedure is repeated using the same proportions except that the emulsifier is a 2.8% solution of potassium 11-perfluoroctyl-hendecanoate in water and 0.113 g. of the water is replaced by that weight of trifluoroethanol, there is obtained after about 118 hours at about 52° C. a milky latex with slight bluish color and no precoagulum, containing 30.4% washed solids corresponding to 86% conversion, with intrinsic viscosity in 2:1 methyl perfluorobutyrate-acetone of 0.11.

Similarly, using a 2.8% aqueous solution of potassium (N-ethylperfluoroctanesulfonamido)-acetate as emulsifier and 0.135 g. of acetone in place of the same weight of water, a cloudy, blue latex with no precoagulum is obtained in about 118 hours at 52° C. The latex contains 28.7% solids, corresponding to 78% conversion; intrinsic viscosity in 2:1 methyl perfluorobutyrate-acetone = 0.20. It is thus seen that the potassium salt of an acid of this invention possesses utility as an emulsifying agent while at the same time the vinyl ester is a polymerizable monomer.

A copolymer is prepared from 20 g. of the above vinyl 11-perfluoroctyl-hendecanoate and 1.47 g. of maleic anhydride (2:1 molar ratio) made up as 50% solution in toluene, to which 1% benzoyl peroxide is added. The mixture is refluxed 14 hours, a further 1% of benzoyl peroxide is added and after heating for 7 hours longer the solution is diluted to 35% solids with methyl ethyl ketone and precipitated with methanol, giving a polymer softening above 60° C. When applied to paper or cloth as a 5% solution in methyl ethyl ketone, and the solvent permitted to evaporate, the paper or cloth is rendered oil and water-repellent.

Example XI

15 Allyl esters are prepared by azeotropic removal of water with benzene or toluene from a mixture of the terminally perfluoroalkyl aliphatic acid and allyl alcohol using a sulfonic acid catalyst for the esterification. Esters are thus prepared from 6.0 g. (0.01 mole) of 11-perfluoroctyl-hendecanoic acid with 5.8 g. (0.10 mole) of allyl alcohol and from 16 g. (0.025 mole) of 11-perfluoroctyl-10-chloro-hendecanoic acid with 10 g. of allyl alcohol, to produce, respectively, allyl 11-perfluoroctyl-hendecanoate and allyl 11-perfluoroctyl-10-chloro-hendecanoate. The esters are purified by distillation under reduced pressure.

Example XII

Following the procedure of Example I above, a mixture of 28.8 g. of perfluoro-(4-ethylcyclohexane)sulfonyl chloride, 9.2 g. of 10-hendecenoic acid and 1.0 g. of di-t-butyl peroxide is heated to 145° C. under reflux and held at that temperature for two hours. The reaction product is subjected to high vacuum distillation in a short path distilling apparatus. The fraction boiling at 130-145° C. at 0.01-0.04 mm. is collected. A pasty brown solid is recovered, and is redistilled at 130° C. and 0.010 mm., to produce a mushy semi-solid comprising 10-chloro-11-perfluoro-(4-ethylcyclohexyl)hendecanoic acid.

40 This product is probably a mixture of stereoisomeric materials, owing to the nature of the perfluoro-4-ethylcyclohexyl group. *Analysis.*—Found, 5.9% Cl; calculated for $4 \text{C}_2\text{F}_5\text{C}_6\text{F}_{10}-\text{CH}_2-\text{CHCl}-(\text{CH}_2)_8-\text{CO}_2\text{H}$ 6.0% Cl.

45 By combination of a fractional melting procedure with recrystallization a solid acid is isolated which is considered to have the "trans" configuration. The crude acid is placed in a heavy-walled centrifuge tube fitted with a sealed-in porous porcelain plate so that upon centrifugation liquid material is readily separated from solid. Centrifuging is started at -25° C. and allowed to proceed until the tube and contents have been warmed to about 39° C. The solid 10-chloro-11-(perfluoro-4-ethylcyclohexyl)-hendecanoic acid thus obtained melts at 46.0° to 48.0° C. *Analysis.*—Found, 37.9% C., 46.1% F, 6.2% Cl; calculated for $\text{C}_{10}\text{H}_{20}\text{F}_{15}\text{O}_2\text{Cl}$, 38.0% C, 47.4% F, 5.9% Cl.

A solution of 14.0 g. (0.023 mole) of the chlorinated acid of melting point 46-48° C. and 4.0 g. (0.1 mole) 60 of sodium hydroxide in a mixture of 40 ml. each of ethanol and water is hydrogenated under 2500 p.s.i. pressure of hydrogen with Raney nickel catalyst for 3 hours at 150° C., followed by 3 hours at 180° C. in a rocking autoclave as in previous examples. The workup furnishes an amber-colored oily acid which is recrystallized from methylene chloride at -25° C. to give the desired 11-(perfluoro-4-ethylcyclohexyl)-hendecanoic acid melting at 55-60° C. *Analysis.*—Found, 41.4% C, 48.6% F; calculated, 40.3% C, 50.8% F.

70 What is claimed is:

1. A compound of the group consisting of terminally perfluoroalkyl-substituted aliphatic carboxylic acids represented by the formula:

75 wherein R_f represents a monovalent, functionally-unsub-

stituted perfluorinated group having from 4 to 12 carbon atoms and R is a straight chain alkylene group having from 1 to 12 carbon atoms, and the carboxyl-linked derivatives thereof selected from the class consisting of cationic salts, cationic complexes, acyl halides, anhydrides, amides, amidines, nitriles, hydrazides, peroxides, esters and orthoesters.

2. A compound of the group consisting of 5-(perfluoroctyl)-pentanoic acid, and the carboxyl-linked derivatives thereof selected from the class consisting of salts, cationic complexes, acyl halides, anhydrides, amides, amidines, nitriles, hydrazides, peroxides, esters and orthoesters. 10

3. A compound of the group consisting of 11-(perfluoroctyl)-hendecanoic acid and the carboxyl-linked derivatives thereof selected from the class consisting of cationic salts, cationic complexes, acyl halides, anhydrides, amides, amidines, nitriles, hydrazides, peroxides, esters and orthoesters.

4. A compound of the group consisting of 11-(perfluoro-4-ethyl-cyclohexyl)hendecanoic acid and the carboxyl-linked derivatives thereof selected from the class consisting of cationic salts, cationic complexes, acyl halides, anhydrides, amides, amidines, nitriles, hydrazides, peroxides, esters and orthoesters.

5. A compound of the group consisting of 12-(perfluoroctyl)dodecanoic acid and the carboxyl-linked derivatives thereof selected from the class consisting of cationic salts, cationic complexes, acyl halides, anhydrides, amides, amidines, nitriles, hydrazides, peroxides, esters and orthoesters. 25

6. 12-(perfluoroctyl)dodecanoic amide.

7. 11-(perfluoroctyl)hendecanoyl chloride.

8. Vinyl 11-(perfluoroctyl)hendecanoate.

9. Sodium 5-(perfluoroctyl)pentanoate.

10. Potassium 11-(perfluoroctyl)-hendecanoate.

11. 11-(perfluoroctyl)-hendecanoic amide.

12. Aluminum 11-(perfluoroctyl)hendecanoate.

13. A polymer of a compound of the formula:

wherein R_f represents a monovalent, functionally-unsubstituted perfluorinated group having 4 to 12 carbon atoms, R is a straight chain alkylene group having 1 to 12 carbon atoms, and n is a number of the group consisting of 0 and 1. 40

14. A process for the production of terminally perfluoroalkylated aliphatic carboxylic acids which comprises subjecting a halogenated acid represented by the formula:

wherein R_f represents a monovalent, functionally unsubstituted perfluorinated group having from 4 to 12 carbon atoms and RX represents a straight-chain alkylene group having from 1 to 12 carbon atoms and having a halogen other than fluorine attached to the carbon atom thereof which is adjacent to the methylene group connected to the said perfluorinated group, to the action of hydrogen under pressure in the presence of a hydrogenation catalyst.

15. A polymer of a compound of the formula:

wherein R_f represents a monovalent, functionally-unsubstituted perfluorinated group having 4 to 12 carbon atoms, R is a straight chain alkylene group having 1 to 12 carbon atoms, and n is a number of the group consisting of 0 and 1.

16. A polymer of vinyl 11-(perfluoroctyl)-hendecanoate.

17. A copolymer of vinyl 11-(perfluoroctyl)-hendecanoate with maleic anhydride.

18. As an article of manufacture, a fibrous material which has been treated with a polymer of a compound of the formula:

wherein R_f represents a monovalent functionally-unsubstituted perfluorinated group having 4 to 12 carbon atoms, R is a straight chain alkylene group having 1 to 12 carbon atoms, and n is a number of the group consisting of 0 and 1.

19. 5-(perfluoroctyl)pentanoic acid.

20. 11-(perfluoroctyl)hendecanoic acid.

21. 11-(perfluoro-4-ethyl-cyclohexyl)-hendecanoic acid.

22. 12-(perfluoroctyl)dodecanoic acid.

35 23. Terminally perfluoroalkyl-substituted aliphatic carboxylic acids of the formula:

wherein R_f represents a monovalent, functionally-unsubstituted perfluorinated radical having from 4 to 12 carbon atoms and R is a straight chain alkylene group having from 1 to 12 carbon atoms.

UNITED STATES PATENT OFFICE
CERTIFICATION OF CORRECTION

Patent No. 2,951,051

August 30, 1960

George V. D. Tiers

It is hereby certified that error appears in the above numbered patent requiring correction and that the said Letters Patent should read as corrected below.

Column 5, line 33, for "xlyene" read -- xylene --;
column 7, line 36, for "10 chloro-" read -- 10-chloro- --;
column 8, line 43, for "4 C₂F₅C₆F₁₀-" read -- 4-C₂F₅C₆F₁₀- --;
column 10, line 24, the formula should appear as shown below
instead of as in the patent:

Signed and sealed this 6th day of June 1961.

UNITED STATES PATENT OFFICE
CERTIFICATION OF CORRECTION

Patent No. 2,951,051

August 30, 1960

George V. D. Tiers

It is hereby certified that error appears in the above numbered patent requiring correction and that the said Letters Patent should read as corrected below.

Column 4, lines 7 to 13, the formula should appear as shown below instead of as in the patent:

column 9, line 38, beginning with "13. A polymer of a compound" strike out all to and including "O and 1.", in line 45, same column 9; in the heading the printed specification, line 8, for "23 Claims." read -- 22 Claims.

--.

Signed and sealed this 31st day of October 1961.
